(57) CLAIM

The ornamental design for a wrist watch case, as shown and described.

DESCRIPTION

FIG. 1 is a top, front and right side perspective view of a wrist watch case showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view; and,

FIG. 7 is a right side elevational view thereof.

The broken line in FIG. 1 is used to show a portion of the wrist watch case that does not form part of the claimed design.
